UNITED STATES PATENT OFFICE

ISIDOR SILBERSTEIN, OF BERLIN, GERMANY

ELECTRIC RESISTANCE

Application filed June 28, 1929, Serial No. 374,376, and in Germany June 30, 1928.

My invention relates to improvements in electric resistances, and more particularly in electric resistances consisting of solid rods and the construction of the connection of the leads thereto. The object of the improvements is to provide a connection for electric resistances which is reliable after long use, and which can be made without spoiling the resistance or the coating thereof. With this object in view my invention consists in providing the resistance with a metallic end piece or end pieces constructed for having the leads connected thereto by pressing parts of the metal on the leads. In the preferred embodiment of the invention I provide the said metallic end piece or end pieces with a groove adapted to have the lead embedded therein and to have its wall pressed inwardly and on the lead.

For the purpose of explaining the invention several examples embodying the same have been shown in the accompanying drawing, in which the same letters of reference have been used in all the views to indicate corresponding parts. In said drawing,

Fig. 1 is an elevation of the resistance having two leads connected thereto,

Fig. 2 is a detail sectional elevation on an enlarged scale showing one of the ends of the resistance and the metal piece carried thereby,

Fig. 3 is an end view looking from the left in Fig. 2,

Fig. 4 is an elevation showing a modification in which the resistance is carried by elastic arms,

Fig. 5 is an elevation showing another modification,

Fig. 6 is a sectional view on an enlarged scale showing a modified form of the end piece, and

Fig. 7 is an end view looking from the left in Fig. 6.

In the example shown in Figs. 1 to 3 a resistance rod *a* has end pieces in the form of cylindrical caps *b* secured thereto. The rod *a* is made from glass or other ceramic material, and it is coated at both ends with layers *c* of copper or other high conductive material insuring a reliable electrical connection between the caps *b* and matter of low conduc-

tivity carried by the rod *a*. In the example shown in the figures the said matter consists of a linear strip *d* of carbon coated by a layer *e* of lacquer indicated in Fig. 2 by cross hatching.

Each cap *b* is made integral with an axial extension *f*, and it is formed with an annular groove *g*. In the manufacture of the resistance the caps *b* are placed on the copper-coated ends of the rod *a*, the leads *h* are formed with eyes, and the said eyes are embedded in the grooves *g*. Now the rod is brought on a press having slightly conical matrices and adapted to press the caps *b* into close contact with the ends of the rod. Simultaneously by the said matrices the margins *i* of the caps *b* are pressed inwardly, thus firmly pressing the eyes of the leads into the grooves *g*. Preferably the leads *h* are tinned at their ends so that a reliable joint is produced between the same and the walls of the grooves *g*.

In the practical use of the resistance the free ends of the leads *h* may be soldered to the contacts of a radio apparatus or the like.

If desired the leads *h* may be cut from the caps *b*, and the resistance may be fitted by means of the extensions *f* between contacts *k* made in the form of leaf springs and placed on a foundation *m*, as is shown in Fig. 4.

In the modification shown in Figs. 5 to 7 in lieu of the grooves *g* formed in the caps *b* rings *n* are fitted on the extensions *f* of the caps *b*, and the said rings are formed with annular grooves *o* for securing the leads *h* thereto, the said leads being formed at their ends with eyes embedded in the said grooves and pressed into contact therewith by bending the marginal parts *p* of the rings *n* inwardly. After thus securing the wire *h* to the ring *n* the said ring is pressed on the extension *f*.

By thus fixing the leads *h* to a separate ring *n* the said ring and the cap *b* may be made from different materials according to the desired use of the resistance. For example the ring *n* may be made from soft metal, so that the margin *p* can be readily pressed into engagement with the lead *h* for pressing the same into the groove *o*. The cap *b* may be
